UNITED STATES PATENT OFFICE.

FRANK JEPHSON WIDDOWSON, OF SOUTH KENSINGTON, LONDON, ENGLAND.

METHOD OF AND MEANS FOR HOLDING NOTES, BILLS, AND OTHER PAPER MONEY.

1,305,326.

Specification of Letters Patent.

Patented June 3, 1919.

Application filed December 19, 1918. Serial No. 267,470.

To all whom it may concern:

Be it known that I, FRANK JEPHSON WIDDOWSON, a subject of the King of Great Britain and Ireland, residing at the Oratory, South Kensington, London, S. W. 7, England, have invented new and useful Improvements in Method of and Means for Holding Notes, Bills, and other Paper Money, of which the following is a specification.

This invention refers to a method of and means for holding notes or bills, or other paper money, of various denominations and offers facilities for the ready withdrawal of a note or notes as required, thereby providing a wide use with railway booking offices, shopkeepers, cashiers, wages clerks and such like.

The method resides in the superposing one denomination of note with respect to another and providing for reversibility, that is to say, in case ten dollar and five dollar bills, by way of example, are being dealt with the device carries one denomination on one side of the table or platform and the other denomination on the other side, so that the power of inversion allows either value of note to be placed in its proper batch or withdrawn with a minimum of trouble.

The means employed may be varied in form and material, and as to this I do not restrict myself and it is obvious that in lieu of reversing the complete device I may arrange to invert the table or platform itself, when necessary, the same being carried on an appropriate stand.

And in order that the invention may be completely understood I have attached three sheets of drawings hereto to which I will refer.

Figure 1 of these drawings shows a front elevation of an appropriate form of my invention.

Fig. 2 is a plan thereof.

Fig. 3 is an end view.

Fig. 4 indicates in front elevation a modification.

Figs. 5 and 6 are respectively plan view and front elevation of a further modification.

In the simplest form of my invention I might use a wood, metal, fiber, composition, or like frame *a*. Two of these frames are

held together and spaced apart any desired distance by means of a rod *b* passed through a hole made in one of the side walls of each of the frames *a*. The frames may be easily moved along the rod *b* to place them the required distance apart. Disposed within the frame *a* is a platform or table *c* about the size of dollar bills, or rather larger, having a pair of rods *d*, *d* on one side and another pair of rods *e*, *e* at the other side. These rods are disposed in pairs at each side of the cross rod *b* and above and below the table *c* and the rods are anchored or suspended by stout elastic cords *f* from studs *g* or the like screwed into the side walls of the frames *a*, the elastic cords of the lower spindles or rods being conducted to the upper studs, and the cords of the upper spindles going to the lower studs, as clearly shown in Fig. 1.

As thus the table or platform is held suspended but is free to yield either upward or downward as required.

In case the upper face of the table is to receive ten dollar bills it is only necessary to press firmly on the table or platform with the bill in the hand when such bill can be instantly slipped into place and on removal of the hand the table *c* rises and secures the bill in place beneath the bars or spindles *d*, *d*. To insert a five dollar bill the entire device is simply inverted and the same procedure followed.

In lieu of elastic bands I may use springs so arranged as to act under compression or extension for my purpose.

In the modification shown in Fig. 4, the frames *a* are permanently secured together by the metal cross stays *h*, although they may be permanently secured by other means such as a panel of wood or the like. In this modification the side members of the frames are formed with slots *a'*, the platform *c* being disposed between two pairs of bars *d*, *d*, *e*, *e*, slidable and guided with such slots. The table *c* is suspended and supported by the elastic bands or cords *f* and the device is operated in the manner described with reference to the preceding figures.

An obvious modification is to provide for the inversion of the table or platform itself and means for effecting this are shown in Figs. 5 and 6.

This construction shows a base board or

plate *i*, carrying supporting brackets *j*. The table or platform *c* carries at each side a pair of cross rods *d*, *d*, and *e*, *e*, secured to the table by stout elastic cords *f*. The upper 5 pair of rods *d*, *d*, are disposed within recesses in the supporting brackets *j* as shown. When the platform is forced downward in the position which is indicated in Fig. 6, a bill of the proper denomination, say ten dollars, can be placed in position, while by reversing the table or platform the same can be made to yield for the purpose of getting a five dollar bill in place. It will be noted that three pairs of brackets are provided. 10 15 On inverting the table the rod *e*, at the left hand of the figures could be accommodated by the bracket to the left, while the other rod *e*, would be placed on the inner one of the pair of brackets to the right. It will be 20 understood that the elastic device shown in these figures could be varied. This construction would allow me to use a device capable of being placed in a shallow drawer and also of the complete removal of the table or platform along with the batches of bills in 25 position in compact form ready for putting into a safe or for counting, withdrawal or otherwise. The stand in this case may be of wood, or of metal and wood or other material or 30 materials as desired.

Devices according to my method provide for the easy and rapid putting away of bills of two denominations and of the equally ready withdrawal of same. 35 Should a greater number of denominations of bills or the like be required to be dealt with, I could provide two platforms which would allow of four values being dealt with. This would in effect amount to a 40 duplication of my duplex arrangement.

The construction of the device described may be varied in mere matter of detail.

I declare that what I claim is.

1. A device for batching, holding or storing notes or bills of different denominations, comprising a table or platform to carry bills of different values on each face, means to elastically suspend such table on end frames and retain the bills, and means to enable the table to be depressed to allow for the reception or withdrawal of notes, the inversion of the device or table allowing for either value of note being placed in its proper batch or removed substantially as described. 50

2. A device for batching, holding or storing notes or bills of different denominations, comprising a pair of frames, means for securing said frames a suitable distance apart, a table slideable within said frames, cross rods to support the table disposed at each 55 side of said table, means to elastically suspend and guide said cross rods and enable the table to be depressed to allow for the reception or withdrawal of notes or bills, substantially as described. 60

3. A device for batching, holding or storing notes or bills of different denominations, comprising a table, cross rods disposed at each side of said table, supports or brackets for the cross rods carried on a base plate to 65 enable the table to be placed either side up, elastic means for securing the cross rods against the table to hold inserted notes or bills and to enable the table to be depressed to permit of the insertion or removal of a 70 note or bill substantially as described. 75

In testimony whereof I have signed my name to this specification.

FRANK JEPHSON WEDDOWSON.
